Associates

Samuel Needham of the same place.

Letters Patent No. 1959 Dated Feb. 6-1866.

Design for Fabric trimming

The schedule referred to in these Letters Patent and making part of the same,

Is as follows:

Be it known that I, Thomas Merry, of Philadelphia, Pennsylvania, have invented or produced a new and original design for a fabric for trimming, and I do hereby declare that the accompanying drawing shows clearly my said design.

I therefore claim as my production The design for a fabric for trimming represented in and by the accompanying drawing.

In testimony whereof I have signed my name to this specification in the presence of two subscribing witnesses.
